UNITED STATES PATENT OFFICE.

WILLIAM SPALCKHAVER, OF NEW YORK, N. Y., ASSIGNOR TO ROBERT HOE,
OF NEW YORK, N. Y.

DELIVERY MECHANISM FOR PRINTING-MACHINES.

SPECIFICATION forming part of Letters Patent No. 732,322, dated June 30, 1903.

Application filed November 8, 1902. Serial No. 130,536. (No model.)

To all whom it may concern:

Be it known that I, WILLIAM SPALCKHAVER, a citizen of the United States, residing at New York, county of Kings, and State of New York, have invented certain new and useful Improvements in Delivery Mechanisms for Printing-Machines, fully described and represented in the following specification and the accompanying drawings, forming a part 10 of the same.

This invention relates to certain improvements in printing-machines.

There is at the present time a demand among users of printing machinery for a machine 15 which will produce a product consisting of a number of stapled sheets folded inside a number of other sheets. This is particularly true of the publishers of newspapers, many of whom desire to issue on certain days a magazine which will form a part of the ordinary 20 paper and which shall be folded inside of the sheets which comprise the ordinary paper. Since, however, this magazine is only issued occasionally, it is not desirable to install special machinery which can only be 25 used for the production of this particular product.

This invention has for its object to produce a delivery mechanism for printing-machines 30 which is capacitated to deliver a plurality of stapled sheets folded inside of other sheets and which is also capacitated to deliver independent products.

With this and other objects in view the invention consists in certain constructions and 35 in certain parts, improvements, and combinations, as will be hereinafter fully described and then specifically pointed out in the claims hereto appended.

In the accompanying drawings, Figure 1 40 illustrates one form of a delivery mechanism embodying the invention. Fig. 2 is a perspective view of one of the products which this delivery mechanism is capacitated to produce. Fig. 3 illustrates a modified form 45 of delivery mechanism.

Referring to the drawings, 1 and 2 illustrate a pair of cutting and folding cylinders of ordinary construction. The web or webs 50 upon which these cylinders operate may be presented to them in any desired way. As

shown, the web is delivered to these cylinders by a pair of rolls 3, which may be the nipping-rolls of an ordinary longitudinal folder, the drawing-off rolls 4 of such folder 55 being shown as located above the nipping-rolls. The sheets produced by the cutting-cylinders 1 and 2 are tucked, by the usual folding-blades 5, between the pair of folding-rolls 6, which rolls deliver the folded sheets 60 to an S-fly 7 of ordinary construction, said fly in turn delivering the sheets to a carrier 8. The agencies which have been above referred to are all well known in the art, and for the purposes of the present invention it is sufficient to indicate them diagrammatically, these agencies having no special reference to the present invention and the devices by which they are operated being well known and being unnecessary to an understanding 70 of the invention.

A second pair of cutting-cylinders (marked 9 and 10) is employed, to which a web is shown as being delivered by means of rolls 11, which, as said in connection with the description of 75 the first delivery mechanism, may be the nipping-rolls of an ordinary longitudinal folder, the drawing-off rolls of this folder being indicated at 12. The cylinder 9 is provided with the usual tucking-blades 13, which deliver the 80 cut sheets to a pair of folding-rollers 14, these rollers in turn delivering the sheets to an S-fly 15, which deposits the sheets on a carrier 16. A diagrammatic illustration of this second delivery mechanism is sufficient for the 85 purposes of the present specification for the reasons stated in connection with the description of the first delivery mechanism.

A stapling mechanism is employed, which coöperates with the second delivery mechanism. This stapling mechanism may be of any of the forms now well known in the art. Preferably, however, the staple forming and driving roll will be arranged to coöperate directly with the cylinder 9, before referred to, said 90 95 stapling-roll being diagrammatically illustrated at 17.

It is apparent that with the construction as so far described a cut and folded product may be delivered by the fly 7 to the carrier 8, and 100 a cut, stapled, and folded product may be delivered to the carrier 16 by the fly 15, or by

throwing out the stapling-rolls, which can be accomplished by any of the ordinary agencies, a cut and folded product may be delivered by the flies to the carriers 8 and 16.

5 When it is desired to employ the mechanism before described to produce a single product consisting of a plurality of stapled sheets folded inside the other sheets, suitable guides are provided. These guides may be varied 10 somewhat in position, depending upon the specific arrangement of the various mechanisms and the way in which it is desired to run the web. Referring to the construction shown in Fig. 1, the stapled web is led directly from the stapling mechanism around a guide 18 and then over a guide 19 to and between the cutting-cylinders 1 and 2. As the stapled web passes around the cylinder 1 it meets the other web and is associated therewith, the two webs 15 20 being cut simultaneously, after which they are tucked between the rolls 6, which deliver the folded product to the fly 7. With this arrangement the cutting-cylinders 9 and 10 are rendered inoperative—as, for instance, by removing the cutting-bar from the cylinder 10 or in any other suitable manner. The mechanism for operating the rolls 14 and the fly 15 may also be thrown out, if desired.

Referring to the construction shown in Fig. 30 3, in which the unstapled web is led to the stapling-delivery, the guides 18 and 19 are employed, as before, and an additional guide 20 is or may be used. In this construction, furthermore, the cutting-cylinder 10 and the 35 stapling-roll 17 are transposed in position. This arrangement, however, produces, as before, a product consisting of stapled sheets folded inside other sheets.

The invention may be embodied in constructions and arrangements different from those which have been hereinbefore de-

scribed. The invention is not, therefore, to be limited to the specific constructions and arrangements of parts described in the foregoing specification and illustrated in the accompanying drawings. 45

What is claimed is—

1. The combination with a cutting and folding mechanism, of means for presenting a web thereto, a delivery mechanism to which said cutting and folding mechanism delivers sheets, a second cutting mechanism, means for presenting a web thereto, a stapling mechanism coöperating therewith, a delivery mechanism to which said second cutting mechanism delivers sheets, said cutting and delivery mechanisms being capacitated for independent use, and guides whereby both webs may be led to one of the cutting mechanisms with the stapled web on the inside, substantially 50 as described.

2. The combination with a cutting and folding mechanism, of means for presenting a web thereto, a delivery mechanism to which said cutting mechanism delivers sheets, a second cutting mechanism comprising a pair of cutting and folding rolls and a pair of nipping-rolls, a stapling-roll coöperating with one of the cutting-rolls, a delivery mechanism to which said second cutting mechanism delivers, said cutting and delivery mechanism being capacitated for independent use, and guides whereby both webs may be led to one of the mechanisms with the stapled web on the inside, substantially 55 as described. 70

In testimony whereof I have hereunto set my hand in the presence of two subscribing witnesses.

WILLIAM SPALCKHAVER.
